UNITED STATES PATENT OFFICE.

MICHAEL MURRAY, OF SOUTH MANCHESTER, CONNECTICUT.

BUFFER FOR LOOMS.

SPECIFICATION forming part of Letters Patent No. 258,461, dated May 23, 1882.

Application filed February 21, 1881. (No model.)

To all whom it may concern:

Be it known that I, MICHAEL MURRAY, of South Manchester, in the county of Hartford and State of Connecticut, have invented a certain new and useful Improvement in Buffers for Looms, of which the following is a description, reference being had to the accompanying drawings, where—

Figure 1 is a view of one end of the lathe-beam of a loom with my improvement attached, and Fig. 2 is a bottom-view of same.

The letter *a* denotes a portion of the lathe-beam; *b*, the shuttle, (shown in dotted lines); *c*, one of the "picker-sticks," whose impulse in the direction denoted by the arrow is commonly communicated through the strap *d*, all this in the common and well-understood manner.

The letter *e* denotes a small crank, pivoted on the under side of the beam, with its lateral arm resting against the back of the picker-stick and pulled inwardly by the spring *f*. The shoulder *g* prevents this crank from moving unduly inward. When it is desired to relieve the picker-stick from the action of the crank, it is done by throwing the crank back, as denoted in dotted lines, and this can be done when the lathe-beam is in motion—when it is "past the center," so to speak, and the spring *f* holds it in that position. Each end of the beam is furnished with this shuttle-buffer. The device eases the shock of the shuttle in stopping, and so prevents the loosening of the

filling on the bobbin and permits the use of a loose or slight tension on the shuttle-binder. 35 The buffer also assists in starting the shuttle on its return travel, and makes the loom operative with less power.

The spring *f* is connected at one end to the lathe-beam by a short leather strap and a 40 screw or stud, and at the other end to the buffer-crank by a leather strap having holes in it, whereby to make it adjustably attachable to the crank. The ends of the spring are attached to the straps by crimping, that being a 45 ready and durable method of attachment.

I am aware that buffers have been used on looms (commonly a piece of raw-hide) singly and in combination with other parts; but these have various defects, which are remedied in 50 my invention.

My improvement consists in the peculiar combination which renders the device readily applicable to any loom and retractile, so that it can be thrown in and out of use promptly 55 and easily while the loom is in operation.

I claim as my invention—

The combination of a lathe-beam, *a*, and a picker-stick, *c*, with the retractile crank *e* and spring *f*, and means for adjustably connecting 60 said spring and crank, all substantially as described.

MICHAEL MURRAY.
